WITNESS:

INVENTOR

ATTORNEY

UNITED STATES PATENT OFFICE

OLE M. AARSETH, OF ECHO, MINNESOTA

MAIL BOX

Application filed July 16, 1928. Serial No. 293,251.

My present invention has reference to a rural mail box and my objects are to mount a mail box on a single bolt with sufficient tension to hold the box reasonably tight on the supporting post so that should the mail collector drive against the box it will be swung out of the way without damage to the box or to the collector, and to further provide the box with a slide door which is hinged to two arms that are themselves hinged or pivoted to the box so that the said door will not extend forwardly from the box toward the road, and when opened will swing over the top of the box and by a slight pressure, will gravitate to closed position, and which will by its own weight, remain in such closed position.

To the attainment of the foregoing the invention consists in the improvement as hereinafter described and definitely claimed.

In the drawings:

Figure 1 is a perspective view of my improvement.

Figure 2 is an approximate longitudinal sectional view.

Figure 3 is a detail sectional view on the line 3—3 of Figure 2.

In the drawings similar reference characters designate corresponding parts throughout.

In the drawings, the numeral 1 indicates a supporting post. On the sides of this post at the top thereof, there are fixed the ends of a substantially U-shaped metal member 2 which may be termed the track for the mail box. Fixed to one of the sides of the track 2, adjacent the outer rounded end thereof, as indicated by the numeral 11, there is the angle end 10 of a metal plate 8 that is arranged below the track.

The mail box 3 has preferably secured to the under face of its bottom 4 a wooden or like strip 5 which rests directly upon the top of the supporting post 1 and on the upper edge of the track 2. There is passed through the bottom 4, the plate 5 and the element 8, the shank of a headed bolt 6, the said bolt having screwed thereon nuts 9 which contact with the opposite faces of the element 8. The bolt is thus held under sufficient tension to

sustain the box reasonably tight on the post and the track. This tension can be adjusted through the medium of the nuts 9.

The box has its open end closed by a slide door 12. The side and top edges of the door are preferably flanged, as at 13, and the bottom of the door may be rolled, as at 14. The plates 15, opposite the rounded lower rolled edge 14 of the door 12 is preferably cut at an inclination, so that the said end 14 of the door may be readily grasped by the mailman for sliding the door over the top of the box 3 in a manner which will now be described. In the showing of the drawings, the door 12 has its outer face, adjacent to its rolled or beaded end 14 formed with spaced ears 16, and in the said showing there is passed through these ears the central portion 17 of a substantially U-shaped member. The arms 18 of the U-shaped member are pivoted or hingedly secured, as at 18', to the sides of the box 3. This is an important feature of the invention, as the door may be readily swung over the top of the box to open the said box and by a slight pressure thereon the said door will slide to closed position, and by virtue of the weight of the door the same will remain in such closed position.

As only a slight pressure is required for closing the door, the said door, should the same remain accidentally open, may be influenced by the wind to cause the same to slide to closed position.

In the showing of the drawings I have illustrated one side of the box provided with a pivotally supporting flag 21, the pivot for the flag being indicated by the numeral 20 and also in the said showing the wire arm of the flag has an angle extension 22 which merges into a hook-shaped end 23. Also in the showing of the drawings I have shown the top of the box provided with a clip or eye member 24 through which is passed the central rounded portion of a wire strand 25. The parallel arms of the wire 25 are twisted upon themselves, as at 26, and from thence extended to provide gripping elements 27 to engage therebetween stamps, etc., the said gripping elements merging into eye members 28. However, I wish it understood that I do

not claim the flag nor the wire member provided with the gripping portions 27, as such are old and well known in the art.

With my improvement it will be noted that 5 should the mail collector drive against the box it will be swung upon its pivot bolt out-of-the-way without damage to the box or to the collector. It will be further noted that I do not employ a hinged door as such doors 10 are not only liable to breakage by the opening and closing thereof, and especially by the outward opening of this type of doors in the direction of the road, but in lieu thereof 15 employ a slide door which is really in the nature of a trap door and which will at all times remain closed by its own weight.

Having described the invention, I claim:

A letter box comprising an elongated receptacle having one end open to form an entrance, a door for said entrance, flanges on 20 the side and upper edges of the door and adapted to engage over the corresponding portions of the receptacle, a rolled flange on the lower edge of the door and projecting below the receptacle, a pair of ears on the door adjacent the lower edge thereof, and a U-shaped member having the ends of the arm portions thereof pivoted to the sides of 25 the receptacle intermediate the ends of the latter, said U-shaped member having the web portion thereof pass through the ears to permit the door to swing upwardly and horizontally over the receptacle.

In testimony whereof I affix my signature.

35 OLE M. AARSETH.
